Patented Oct. 21, 1919.

UNITED STATES PATENT OFFICE.

GEORGE W. MATTERN, OF DAYTON, OHIO, ASSIGNOR TO THE CRAWFORD, McGREGOR AND CANBY CO., OF DAYTON, OHIO, A CORPORATION OF OHIO.

GOLF-CLUB.

1,319,233.

Specification of Letters Patent.

Patented Oct. 21, 1919.

Application filed November 2, 1916. Serial No. 129,126.

To all whom it may concern:

Be it known that I, GEORGE W. MATTERN, citizen of the United States, residing at Dayton, in the county of Montgomery and 5 State of Ohio, have invented certain new and useful Improvements in Golf-Clubs, of which the following is a specification.

My invention relates to golf clubs and more particularly to the mode of weighting 10 or balancing the club by the addition of a body of metal thereto.

The object of the invention is to increase 15 the efficiency of the club by improving its driving power and the accuracy of the stroke by embodying in the head of the club a peculiarly shaped body of metal as herein-after described.

A further object of the invention is to minimize the tendency of an unskilled player 20 to slice or to hook in the event that the ball is engaged toward the heel or the toe of the club.

With the above primary and other incidental objects in view as will more fully appear in the specifications, the invention consists of the features of construction the parts 25 and combinations thereof and the mode of operation of their equivalent as hereinafter described and set forth in the claims.

Referring to the drawing Figure 1 is a perspective view of the head of a golf club in which the invention forming the subject matter hereof has been embodied. Fig. 2 is a similar view of the head of a golf 30 club prepared to receive the weight. Fig. 3 is a perspective view of the balance weight detached from the club. Fig. 4 is a top plan view of the head of a golf club embodying a weight of small size and illustrating by dotted lines the relative position 35 and direction of the attachment screws. Fig. 5 is a similar view of a golf club head embodying a weight of larger size. Fig. 6 is a transverse sectional view of golf club head 40 with the balance weight embodied therein.

Like parts are indicated by like characters of reference throughout the several views.

It has not been unusual in the past to 50 modify the balance or heft of a golf club by the addition thereto of a metallic counter-balance or weight embedded in or attached to the head of the club. However the tend-

ency has been heretofore to concentrate this weight as nearly as possible in alinement 55 with the center of the striking face or theoretically point of contact with the ball. If the ball is always engaged with absolute accuracy this concentration of the weight is not objectionable. However a novice and 60 some experienced players frequently engage the ball adjacent to the heel or to the toe of the golf club head, thereby causing the player to "slice" or to "hook." The concentrated weight being out of alinement to one 65 side or the other of the impact point, the weight tends to turn the club about the point of impact as a center causing the club to 70 swerve in one direction or the other thereby magnifying the inaccuracy of the stroke. 75 Thus the concentrated weight while adding to the efficiency of the skilful player who engages the ball with extreme accuracy in alinement with the weight, is a detriment to the unskilled player, serving to increase the error of his stroke.

This difficulty is overcome in the present instance by distributing the balance weight throughout a length equal to or greater than the striking face, whereby some portion of 80 the counter weight will be in alinement with the point of impact at whatever point on the striking face the ball is engaged.

The counter-balance or weight is shaped to conform to the usual outline of the golf 85 club head. While a preponderance of metal is provided adjacent to the central line or in alinement with the theoretical impact point, it is to be noted that the variation of weight throughout the length of the golf 90 club head is not abrupt but the weight is more uniformly distributed than is usual and extends throughout the whole length of the striking face.

Not only is the weight distributed 95 throughout the whole length of the striking face but the counter-balance or weight is so shaped that its greatest depth or preponderance of material is found in a horizontal plane on a level with the point of impact with 100 the ball. This concentration of weight in a horizontal plane coincident with point of impact tends to overcome the tendency of the club head to tilt forwardly or rearwardly in the event that the player "tops" or 105 "scoffs" the ball. Heretofore a counter-bal-

ance weight has been provided which is of substantially equal thickness throughout, and which extends entirely through the head of the club. It is to be noted that in the 5 present instance the weight body varies in thickness from the thickness of the club head to a sharp edge on the medial plane.

In the drawings, 1 is the head of the golf club of which 2 is the shaft or handle. The 10 head 1 may be of any desired or usual shape or proportion. The forward side of the head 1 is flat as at 3 to form the striking face which is reinforced by the usual insert 4. However as much as the insert 4 forms 15 no part of such invention it may be omitted or modified to suit the conditions of use or the desires of the player.

The rear side of the head 1 or that side opposite the striking face 3 is provided with 20 a horizontally disposed V shaped groove or recess as shown at 5 in Fig. 2. Embedded within the recess 5 and conforming closely thereto is a metallic counter-balance or weight 6, shown in detail in Fig. 3. The 25 outer face of the weight is shaped to conform with the contour of the head 1. The counter-balance or weight may be of any desired size and may extend more or less deeply into the head 1 as shown by the relative proportion of the weight 6 in Figs. 4 and 5. The tapered or V shape of the groove 5 not only affords a maximum amount of metal in a substantially horizontal plane approximately coincident with the normal 30 point of impact but it also serves to anchor the weight 6 to prevent its vertical displacement under centrifugal tendency as the club is swung to and fro or under the influence of the shock due to impact with the ball. It 35 will be noted by reference to the drawing that the V shaped groove 5 is equal to or greater than the length of the striking face 3. Thus at whatever point of the striking face the ball may be engaged sufficient metal 40 will be found behind the point of impact to afford increased driving power. Furthermore the weight being distributed more uniformly throughout the length of the striking face than in the devices heretofore used 45 there will be less tendency of the club to swerve and less tendency of the player to "slice" or to "hook," thereby increasing the accuracy of the flight of the ball. By reference to Fig. 6 it is to be noted that the apex 50 of the counter-balance or weight and therefore its center of gravity, is substantially on level with the center of gravity of the ball.

Before placing the counter-balance or weight 6 within the V shaped groove 5 the faces of the groove are coated with non-drying cement or coating material which prevents the material of head 1 from drying and shrinking away from the weight thereby loosening the weight in the head.

65 To rigidly secure the weight 6 in position

two attachment screws 7 are employed. These screws as shown in Figs. 4 and 5 are inserted through the weight 6 and secured into the body of the golf club head in diagonal relation one with the other. The diagonal or inclined relation of the attachment screws 7 serves to securely anchor the counter-balance or weight and distribute the strain in such a way that there is little tendency of the weight to loosen or draw the 75 screws from their engagement with the head 1. To afford a finished surface and furthermore securely anchor the attachment screws 7, the said screws are counter sunk within the weight 6 as shown in Figs. 4, 5, and 6, 80 and the counter sink above the head of the screw is filled with the metal as shown at 8. This may be a metallic plug soldered, brazed or sweated into place, or the counter sink 85 may be filled with molten metal. In the latter event the sides of the countersink are preferably undercut or provided with laterally disposed holes or sockets as at 9, into which the molten metal runs to securely anchor the closure plug or mask 8 in place. 90

By the construction described greater distance on the drive and accuracy of flight of the ball may be secured even where the stroke is not accurately delivered and with accuracy in driving the efficiency of the 95 player is materially increased. The angular relation of the attachment screws and the V shaped recess 5 securely holds the balance weight against accidental displacement so that accuracy in driving is not affected by 100 any looseness or play of the counter-weight.

From the above description it will be apparent that there is thus provided a device of the character described, possessing the particular features of advantage before 105 enumerated as desirable but which obviously is susceptible of modification in its form, proportion, detail construction of arrangement of parts without departing from the principle involved or sacrificing any of its 110 advantages.

While in order to comply with the statute, the invention has been described in language more or less specific as to certain structural features, it is to be understood that the 115 invention is not limited to any specific details, but that the means and construction herein described comprise but one mode of putting the invention into effect, and the invention is therefore claimed broadly in 120 any of its possible forms or modifications within the scope of the appended claims.

Having thus described my invention I claim—

1. In a golf club a head provided with 125 a striking face at its forward side and having in its rear face a substantially horizontally disposed grooved recess extending transversely throughout the length of the striking face and vertically throughout the 130

thickness of the head, a weight seated within said recess, the top and bottom surfaces of the head and weight being flush one with the other and continuous, and means for securing said weight in position.

2. In a golf club, a head provided with a striking surface on its forward side, a wedge-shaped weight secured to the rear face of said head with its prism line horizontally disposed and extending throughout the length of the striking face whereby a portion of the weight will be in the line of force of any point of contact upon the striking face.

3. In a golf club, a head provided with a striking face upon its forward side, and having a substantially horizontally disposed groove in its rear face extending throughout the length of the striking face, a preformed weight seated in said groove, and means for securing the weight in position.

4. In a golf club, a head provided with a striking face upon its forward side, and having a substantially horizontally disposed V shaped groove in the rear face thereof, the edges of said groove being substantially coincident with the top and bottom surfaces of the head, a weight fitted in said V shaped groove and means for drawing said weight to a firm seat in said groove.

5. In a golf club, a head provided with a striking face upon its forward side, and having a substantially horizontally disposed V shaped recess in its rear face extending transversely throughout the length of the striking face and vertically from the top to the bottom surfaces of the head, a

weight fitted in said groove and means to retain the weight in position.

6. In a golf club, a head provided with a striking face upon its forward side, and having a substantially horizontally disposed grooved recess in the rear face of said head, a weight seated in said grooved recess, and attachment members extended through said weight and engaged in the head, said attachment members being extended in different directions angularly disposed.

7. In a golf club, a head having a striking face upon its forward side and having a pocket having substantially straight divergent sides formed in the rear face of said head, a preformed weight member having like divergent sides adapted to fit within said pocket and means for drawing the weight to a firm seat within said pocket as described.

8. In a golf club, a head having a striking face upon its forward side and an angular socket in its rearward side, a preformed weight having angularly arranged faces positioned in said angular socket, and a pair of screws diagonally positioned in relation one with the other engaging said preformed weight and head whereby the weight is drawn into firm seating contact with the head, substantially as specified.

In testimony whereof, I have hereunto set my hand this 30th day of Oct., A. D. 1916.

GEORGE W. MATTERN.
